(57) **CLAIM**

The ornamental design for a vehicle as shown and described.

DESCRIPTION

FIG. 1 depicts a front, left, upper perspective view of a vehicle showing our new design.

FIG. 2 depicts a front, right, lower perspective view thereof;

FIG. 3 depicts a rear, right, upper perspective view thereof;

FIG. 4 depicts a front view thereof;

FIG. 5 depicts a back view thereof;

FIG. 6 depicts a left side view thereof;

FIG. 7 depicts a right side view thereof;

FIG. 8 depicts a top view thereof; and,

FIG. 9 depicts a bottom view thereof.

The ghosted or low contrasted showing of the vehicle is provided for the purposes of illustrating portions that form no part of the claimed design. The dash lines represent boundaries of the claimed design.

1 Claim, 9 Drawing Sheets
